UNITED STATES PATENT OFFICE.

ALLAN G. WOODFORD, OF JERSEY CITY, NEW JERSEY, ASSIGNOR TO
INTERNATIONAL CIGAR MACHINERY COMPANY, OF NEW YORK,
N. Y., A CORPORATION OF NEW JERSEY.

CUTTING MECHANISM FOR CIGAR-MACHINES.

No. 817,830.

Specification of Letters Patent.

Patented April 17, 1906.

Application filed April 9, 1904. Serial No. 202,317.

To all whom it may concern:

Be it known that I, ALLAN G. WOODFORD, a citizen of the United States, residing at Jersey City, county of Hudson, and State of New

5 Jersey, have invented certain new and useful Improvements in Cutting Mechanism for Cigar-Machines, fully described and represented in the following specification and the accompanying drawings, forming a part of the 10 same.

This invention relates to certain improvements in cutting mechanism for cigar-machines.

In an application filed by Oluf Tyberg on 15 August 27, 1901, serially numbered 73,409, there is disclosed an automatic machine in which after the cigar has been wrapped by a suitable mechanism it is taken by a movable carrier and transported to a delivery mechanism. In this machine the trimming of the cigar is effected while the cigar is in the movable carrier by means of suitable cutting devices which are automatically moved into and out of the path of the carrier. It sometimes happens, however, that the wrapping mechanism will fail to properly wind the wrapper on the bunch, so that an imperfect cigar is produced. If, however, this imperfect cigar be operated upon by the cutting or 25 trimming devices before referred to, the bunch will be too short to be again put through the wrapping mechanism, and it is consequently wasted.

The present invention has for its object to 30 produce an improved cutting mechanism by which a cigar is trimmed after being wrapped and while in the movable carrier, the cutting devices being movable into and out of the path of the carrier and means being provided 35 to interrupt the action of the trimming mechanism whenever desired and without interrupting the operation of the rest of the machine.

With this and other objects not specifically 40 referred to in view the invention consists in certain constructions and in certain parts, improvements, and combinations, such as will be hereinafter fully described and then 45 specifically pointed out in the claims hereunto appended.

Referring to the drawings, Figure 1 illustrates in side elevation so much of the oper-

ating mechanism of a cigar-machine and its cutting devices as is necessary to an understanding of the invention. Figs. 2 and 3 are 55 detail views.

Referring to the drawings, the type of cigar-machine which has been selected to illustrate the invention is a machine for making cheroots, and for that reason the cutting devices hereinafter referred to are of such a character as to trim both ends of the wrapped cigar. It is apparent, however, that the invention might be used with other types of machines.

According to the present invention the cigar after being wrapped by mechanism (not shown) is taken by a carrier. This carrier may be of any suitable construction. In the form selected to illustrate the invention there is provided an arm 120, which is mounted on a vertical shaft 121, this shaft being rotated in any suitable manner to produce the desired movement of the carrier. A description of the means for rotating this shaft is not necessary to an understanding of the present invention, and such a description is therefore not given. Reference is made, however, to the application before referred to for a full disclosure of suitable means which may be employed for this purpose. The arm 120 of the construction illustrated is provided with a casting 128, having downwardly-extending projections 130 and 131, which projections are suitably formed to receive the ends of the cigars. Between these projections and on each side of the carrier are mounted a series of supporting-fingers 137, these fingers being supported on rocking rods 134. In the construction chosen to illustrate the invention the carrier is provided with an ejector 138, which is located between the fingers 137 and the action of which opens the fingers, this ejector being mounted on a stem 139, slidingly mounted in the arm 120.

The operation of the ejector and the opening of the fingers are produced by means of a rocking arm 147, having a slotted end, said arm engaging a pin 146 on the ejector-stem. The means for operating this arm and the means by which the ejector effects the opening of the fingers are unnecessary to an understanding of the present invention and no description thereof is given. Reference is,

however, made to the application before referred to for a full disclosure of suitable means which may be employed for this purpose.

The cutter by which the trimming of the cigar is effected may be varied in form and construction. As shown, however, the cutter consists of rotating disks 190, mounted on a shaft 191, two of these disks being employed, as has been before stated, because the particular mechanism in which the invention is embodied is a cheroo-machine. Inasmuch as the cutter is to be moved into and out of the path of the carrier at proper times, suitable means will be provided for effecting this movement. While these means may vary, in the construction shown the cutter-shaft 191 is mounted on suitable bearings on a slide-block 192, said block being mounted in ways in a bracket 193, suitably secured to the machine-frame. The cutters may be rotated in any suitable manner. As shown, the shaft 191 is provided with a spiral gear 201, which meshes with a gear 202, mounted on a shaft 203, which is suitably supported in the machine-frame. This shaft is provided near its lower end with a gear 204, which is splined thereto and which is driven by suitable connections (not shown) from the cigar-machine. The means for effecting the movement of the cutter-head may be of any suitable character. As shown, the head has connected to it a link 194, said link including a suitable adjusting-turnbuckle 195. The driving mechanism by which the link is actuated may be of any suitable character. As shown, however, it embodies a bell-crank lever 196 197, pivoted at 198 to a bracket on the machine-frame. The arm 197 is formed with a cam-head 198, which is operated upon by a stud 199, carried on a gear 33, which is driven in any suitable manner from any moving part of the machine. The bell-crank is returned after being operated upon by the stud by means of a suitable spring 200.

The connection between the bell-crank lever 196 197 and the operating connecting-link 194 is of such a character that the operation of the bell-crank may be interrupted at any desired time. While this connection may be of any desired character, as shown, the link 194 is provided with an open hook 605, which engages a stud 606 on the arm 196 of the bell-crank lever. By swinging the link 194, therefore, it is obvious that the connection between the lever and the link will be interrupted. The means for swinging this link may be of any desired character. As shown, there is provided a small bell-crank lever 607 608, said lever being pivoted at 609 to the machine-frame. Means for operating this bell-crank may be of any desired character. As shown, however, the arm 608 has connected to it a swinging link 610, which leads to a suitable treadle 611, which is actu-

ated by the foot of the operator. The arm 607 is so located that when the treadle is operated it will strike the arm 194 and disconnect the hook 605 from the stud 606. The reengagement of the link with the stud on the bell-crank will be effected in any desired manner—as, for instance, by means of a spring 612. A second spring 613 may, if desired, be employed to retract the bell-crank lever 606 607. It is apparent that whenever an imperfect cigar is taken by the carrier before referred to the operator can by pressing on the treadle through the means described prevent the movement of the cutter, and the imperfect cigar will therefore pass the cutter without being trimmed. The bunch after being discharged by the carrier can then be again subjected to the action of the wrapping mechanism.

Changes and variations may be made in the construction by which this invention is carried into effect. The invention is not, therefore, to be limited to the details of construction herein shown and described.

What is claimed is—

1. In a cigar-machine, the combination with a movable cigar-carrier, of a cutter, means for moving the cutter into and out of the path of the carrier to trim the cigar therein, and means for intermitting when desired the operation of said cutter-moving means while the carrier is passing the cutter, to prevent the cigar from being trimmed.

2. In a cigar-machine, the combination with a movable cigar-carrier, of a cutter, means for moving the cutter into and out of the path of the carrier, and devices under the control of the operator for intermitting when desired the operation of the moving means while the carrier is passing the cutter, to prevent the cigar from being trimmed.

3. In a cigar-machine, the combination with a movable carrier, of a cutter, a sliding head in which said cutter is mounted, a suitable moving means, a driver, disconnectible connections between the driver and the head, and means under the control of the operator whereby said connections may be interrupted when desired, substantially as described.

4. In a cigar-machine, the combination with a movable carrier, of a cutter, a sliding head, driving means including a lever, a link connection between the head and the lever, and means under the control of the operator for disconnecting the link from the lever, substantially as described.

5. In a cigar-machine, the combination with a movable carrier, of a cutter, a sliding head in which the cutter is mounted, driving means including a lever, a stud on the lever, a link having an open hook engaging the stud and pivoted to the head, and tripping devices under the control of the operator for disconnecting the link from the stud, substantially as described.

6. In a cigar-machine, the combination with a movable carrier, of a cutter, a sliding head in which the cutter is mounted, driving means including a lever, a stud on the lever, 5 a link having an open hook engaging the stud and pivoted to the head, and tripping devices including a suitable lever under the control of the operator for disconnecting the link from the stud, substantially as described.
- 10 7. In a cigar-machine, the combination with a movable carrier, of a cutter, a sliding head in which the cutter is mounted, driving means including a lever, a stud on the lever, a link having an open hook engaging the stud 15 and pivoted to the head, and tripping de-
- VICES under the control of the operator for disconnecting the link from the stud, said tripping devices including a stud and a suitable lever, and means causing the hooked link to reengage with said stud when the 20 tripping devices are released, substantially as described.

In testimony whereof I have hereunto set my hand in the presence of two subscribing witnesses.

ALLAN G. WOODFORD.
